Application June 27, 1944, Serial No. 542,366

4 Claims. (Cl. 15—97)

This invention relates to portable motorized polishing apparatus and refers more particularly to such an apparatus suitable for polishing automobiles and the like.

An object of the present invention is to provide a device primarily adapted to eliminate the great amount of motion performed by the arm of a person polishing an automobile by means of a cloth held in the hand, and thus eliminate the consequent fatigue.

Such a device must be light, of simple design, have few parts, and the polishing surface must be replaceable at low cost.

Another object is to provide such a machine which will serve a variety of purposes by the use of polishing discs with different kinds of surfaces, such as abrasive, nappy or smooth.

Other objects will become apparent from the following specification.

In accomplishing the objects of the present invention it was found desirable to provide a small electric motor with a hand grip set at right angles to the shaft, and the end of the shaft squared and tapped. Over the squared shaft is slipped a hollow fastener consisting of a disc with a square central hole, cylindrical sides and a circular rim, the member being fastened on by a lock washer and screw engaging the threads in the shaft end. Rivets, counterpins or similar means may be also employed for securing the disc to the shaft.

The rim is slotted to form arms which are bent upward and inserted in corresponding holes in a spring steel locking circle placed over the rim, and the arms are bent down again to fasten the locking circle securely.

The circumference of the locking circle bears a plurality of points extending perpendicularly to the plane thereof, and the center is concave and has an oblong hole and convex portions on either side of the hole, the joint axis of the convex portions forming a cross with the axis of the hole. A circular face piece has a cloth covered face, points extending perpendicularly from the opposite surface, and a countersunk central hole to receive the locking lug, which is a cylindrical piece with a transverse bar at one end and a slotted cloth covered head at the other.

The polishing disc is a cloth with a nappy surface sewn to several thicknesses of ordinary cloth. The nappy cloth and the several adjacent thicknesses have a central circular hole just larger than the face piece, forming a recess in the face. The other several thicknesses have a central hole to permit the passage of the locking lug.

In operation the locking lug is passed through the polishing disc, and the points on the back of the face piece are pressed into the rear several thicknesses of cloth forming the bottom of the recess of the face.

The polishing disc is pressed down onto the points of the locking circle, and then the bar of the lug is passed through the hole in the locking circle and turned through 90 degrees in either direction. The apparatus is then ready for use.

The invention will appear more clearly from the following detailed description when taken in connection with the accompanying drawings showing, by way of example, preferred embodiments of the inventive idea.

In the drawings

Figure 1 is an elevation of an apparatus embodying the present invention.

Figure 2 is a section along the line 2—2 of Figure 3.

Figure 3 is a partial section of the polishing disc along line 3—3 of Figure 2.

Figure 4 is an elevation of the end of the motor shaft, showing the tapped hole therein in broken lines.

Figure 5 is an end view of the shaft.

Figure 6 is another elevation of the shaft end.

Figure 7 is a perspective view of the locking lug.

Figure 8 is a section along the line 8—8 of Figure 2.

Figure 9 is a vertical section of part of the locking lug.

Figure 10 is a perspective view of the fastener.

Figure 11 is a vertical section of the same.

Figure 12 is a perspective view of the locking circle.

Figure 13 is a vertical section of the same.

Figure 14 is a perspective view of the face piece.

Figure 15 is a vertical section of the same.

In the device illustrated, Figure 1 shows the relation of the various parts. The motor 16, has a toggle switch 17 and is mounted on a hand grip 18, in which the wires 61 are enclosed and from which they lead to a source of power. The end of the motor shaft 19 is squared as at 22, 23 in Figures 4, 5, and 6 and drilled and tapped, 20, Figures 4 and 5, parallel to its axis.

The fastener 25, Figures 1, 2, 10, 11, preferably of sheet steel, consists of a circular rim 26 with a concentric substantially cylindrical depressed portion consisting of the side wall 28 and bottom 29. In the bottom is a square central hole 30 which fits on the squared end 22 of the shaft 19. A screw 24, fitting tightly in threads 20, engages the bottom 28 adjacent the hole 30 and causes

the fastener to seat firmly on surface 21, Figures 4 and 5, which is the portion of the shaft end outside the squared portion and at the base thereof. The straight sides 22 of the squared end engage the sides of the square hole 30 to rotate fastener 25 when shaft 19 is rotated. The rim 26 is slotted to form arms 27 which are bent perpendicular to the rim in the opposite direction from the depressed portion, 28, 29.

The locking circle or piece 31 is composed preferably of spring steel and consists of the disc 32 Figures 1, 2, 12, 13, in which are holes 33 corresponding to the arms 27 of fastener 25. It is placed over the fastener with the arms 27 of the fastener extending through the holes 33 (Figure 2), and the arms are then bent outward and down, fastening the locking circle securely to the shaft in a plane perpendicular thereto. A central circular portion 35 of the face of the locking circle is concave and in it is formed a transverse rectangular hole 37. Perpendicular to the median line of the hole two convex portions 36 are formed in the concave portion 35. The rear surface 38 of these convex portions is of course concave. A plurality of points or teeth 34 are mounted about the periphery of the disc 32, perpendicular thereto and facing outward.

The face piece 39 Figures 1, 2, 14, 15 is a disc 44 with inward facing teeth 45 perpendicularly arranged about its periphery, formed with a central hole 42 and a conically sloping surface 41 around the hole to form a seat for the conical surface 51, Figure 7 of the head 52 of the locking lug 46. The lug consists of the head 52, which has a slot 53 and is covered with a nappy material 54 as shown in Figure 9. The head is carried on a body 50, the other end of which carries a transverse bar 47 the same width as the body 50, the length and width of bar 47 being adapted to pass through hole 37 in locking circle 31 as shown in Figure 8. The inner surface 48 of the bar constitutes segments of a cone, and corresponds to the rear surfaces 38 of the convex portions of the locking circle, and rests therein in operation. As shown at 40, Figures 14 and 15, disc 44 including surface 41 has been parted in order to permit the introduction of the locking lug 46 into the hole 42, which is too small to permit passage of either the head 52 or bar 47. It is then welded, soldered or otherwise joined together and the face thereof covered with nappy material.

The polishing disc consists of several cloth circles 56, Figures 2, 3, with central circular holes 57 about the size of head 52 of locking lug 46 and several more circles 58 with central circular holes 59 just larger than face piece 39, and a circle of nappy material 60 the same size as circles 58, all sewed together concentrically, or joined by other means.

In operation the user has but three parts to manipulate. The first is the motor, to the shaft of which is firmly though removably fixed the fastener 25 and locking circle 31. The second is the face piece in which the locking lug has been rotatably fixed. The third is the polishing disc. The face piece is inserted in the larger circle 58 in the face of the polishing disc and the points 45 pressed home into the back layers of cloth 56. Bar 47 of locking lug 46 is now passed through hole 37 in locking circle 31 as shown in Figure 8.

Referring now to Figure 13, it will be seen that the back surface of concave portion 35 through which bar 47 has just passed is convex. The inner surface 48 of bar 47 has an opposite curve,

corresponding to the surface 38, and constitutes a cam, and on the bar being rotated a quarter turn in either direction by means of a screw driver, small coin or the like in slot 53, it will cause the entire disc 32, which is of resilient construction, to belly momentarily in the direction of the points 34, until it comes in coincidence with concave surface 38 to which it corresponds, when disc 32 will assume its original position. The cloth circles 56 may now be pressed down on points 34, the lug has now fastened the face piece to the locking circle in a manner which will be unaffected by rotation, and the polisher is ready for use.

It will be observed that the locking lug 46 and face piece 39 are not only both cloth covered, but are also recessed in the polishing disc 56 so that it is impossible for them to scratch the finish of an automobile or other article being polished.

It is also evident that the polishing disc may be very cheaply manufactured and is the only part subject to even moderate deterioration, and that all parts are of simple and inexpensive design. The polishing disc may be considered disposable in the truest sense, as it consists merely of sewn cloth, having no metal parts or fittings to add to its cost.

It is apparent that the specific illustrations shown above have been given by way of illustration only and not by way of limitation, and that the structures above described are subject to wide variation and modification without departing from the scope or intent of the invention, all of which variations and modifications are to be included within the scope of the present invention.

What is claimed is:

1. A portable apparatus for polishing and the like comprising an electric motor, said motor comprising a motor shaft, a fastener firmly mounted on said shaft, said fastener comprising a rim portion and a cylindrical portion concentric with said rim portion, a locking circle firmly attached to said fastener, said locking circle comprising a resilient disc and a plurality of points substantially on the periphery of said disc and extending perpendicularly thereto, said disc comprising a central portion depressed in a direction opposite to said points, said portion having the shape of part of a sphere, said portion further having a rectangular hole formed therein, parts of said portion further being depressed in the same direction as said points, said parts being located substantially midway of the length of said hole and on opposite sides thereof, a polishing disc, a face piece comprising a substantially stiff disc, said stiff disc being formed with a central hole, a lug extending through said hole, said lug comprising a head, a cylindrical body and a bar extending perpendicularly to said body, said bar being adapted to pass through said rectangular hole and to engage said depressed parts by being rotated through ninety degrees whereby said polishing disc, said face piece and said lug are locked to said locking circle.

2. In a polishing apparatus according to claim 1, said rim portion comprising arms formed out of the material of said rim portion, said resilient disc having holes formed therein corresponding to said arms, said arms extending through said holes whereby said disc is firmly joined to said fastener, said polishing disc comprising a polishing surface and being formed with a central cir-

cular recess in said surface for said face piece, said face piece further being formed with a recess for said lug head said face piece and said lug further comprising nappy material firmly affixed to their outer surfaces.

3. A portable apparatus for polishing and the like, said apparatus comprising an electric motor, a motor shaft carried by said motor and having a projecting end, a polishing disc having a central opening and an outer annular nappy polishing surface, and removable means having parts extending through said central opening, said removable means connecting said polishing disc to the projecting end of said motor shaft and having nappy polishing surfaces extending substantially flush with said annular nappy surface to cover said central opening.

4. A portable apparatus for polishing and the

like, said apparatus comprising an electric motor, a motor shaft carried by said motor and having a projecting end, a fastener having a central portion mounted upon said projecting end and an annular portion, a removable polishing disc having a central opening formed therein, a substantially disc-shaped locking piece, carried by said annular portion of the fastener and engaging one side of said polishing disc, said polishing disc being concentric with said locking piece, a face piece engaging the other side of said polishing disc, and a locking lug engaging said face piece and extending through said central opening, said locking lug being adapted on revolution through a fraction of a turn to lockingly engage said locking piece.
